JOHN ROWE, OF CINCINNATI, OHIO.

Design No. 3,460, dated April 27, 1869.

DESIGN FOR A STOVE.

The Schedule referred to in these Letters Patent and making part of the same.

To all whom it may concern:

Be it known that I, JOHN ROWE, of the city of Cincinnati, and State of Ohio, have originated and designed a new Design for Stoves; and I hereby declare the accompanying drawing, which is made part of this specification, to form a full, clear, and exact delineation of the same.

What I claim as new, and desire to secure by Letters Patent, is—

The ornamental design for stoves, substantially as herein exhibited.

Witnesses:

M. B. PHILIPP,
H. MOORE.
